REUBEN B. BENJAMIN, OF CHICAGO, ILLINOIS, ASSIGNOR TO BENJAMIN ELECTRIC MFG. COMPANY, OF CHICAGO, ILLINOIS, A CORPORATION OF ILLINOIS.

LAMP-CLAMPING SOCKET.

1,167,473.

Specification of Letters Patent.

Patented Jan. 11, 1916.

Application filed April 11, 1913. Serial No. 760,478.

To all whom it may concern:

Be it known that I, REUBEN B. BENJAMIN, a citizen of the United States, residing at Chicago, in the county of Cook and State 5 of Illinois, have invented new and useful Improvements in Lamp-Clamping Sockets, of which the following is a full, clear, concise, and exact description, reference being had to the accompanying drawing, forming 10 a part of this specification.

My invention pertains to lamp clamping sockets; that is to say, to sockets of the kind in which means are provided for clamping the lamp against accidental loosening, due 15 to vibration or like causes.

It is the principal object of my invention to improve upon sockets of this character and to provide for a simple and economical construction which will permit the lamp to 20 be efficiently retained in the socket in spite of any shaking or vibration which may be imparted to the latter.

Two forms of socket embodying my invention are described, by way of example, in 25 the following specification and shown in the accompanying drawings, but it is to be understood that the invention may be embodied in other constructions than those shown and described, without exceeding the scope there- 30 of as defined in the appended claims.

In the drawings: Figure 1 is an inverted plan of a lamp clamping socket constructed in accordance with my invention; Fig. 2 is a side elevation of the same with the 35 lower part shown in vertical section; Fig. 3 is a section on the line 3—3 of Fig. 2, looking in the direction of the arrows; Fig. 4 is a detail perspective view of the lamp clamping member; Fig. 5 is a sectional ele- 40 vation of another form of socket constructed in accordance with my invention; Fig. 6 is a view similar to Fig. 5 but looking in a direction at right angles to that from which Fig. 5 is viewed; Fig. 7 is a view similar to 45 Fig. 5, a lamp being shown in the socket and the clamping member being pressed inwardly; Fig. 8 is an inverted plan of the socket; and Fig. 9 is a perspective detail view of one of the clamping members.

Like reference characters refer to like parts throughout the following specification and the several figures of the accompanying drawings.

The socket shown in Figs. 1-3 is of a 55 kind the general construction of which is

well known in the art. It includes a base member 10, which supports the center contact 11, and to which is secured a second base member 12, which carries the threaded contact 13.

The upper end of the chamber 14 is enlarged so as to form a rectangular chamber 15, the sides of which are curved, at 16 so as to accommodate the threaded shell 13. A U-shaped member, consisting of two arms 17, connected by a cross-piece 18, is mounted in the chamber 15, with its arms 17 in engagement with the side walls of the chamber, whereby lateral movement of these arms is prevented. The U-shaped member is made of a single piece of stout wire, bent into the form shown, so that the middle portions of the arms 17 are enabled to spring away from each other, into the curved portions 16 of the chamber, when lateral pressure is applied to their inside edges. The arms 17 pass through slots 19, formed in the shell 13 so as to follow the threads thereof, the U-shaped member thus assuming the tilted position shown in Fig. 2. The U-shaped member is held against vertical movement by reason of its engagement with the upper and lower edges of the slots 19.

It will be seen from the above description that the middle parts of the arms 17 project within the normal inner surface of the threaded sleeve 13, and that, these arms being resilient, they can be sprung out to follow the surface of the threaded sleeve 13 when pressure is applied to their inner edges. When a lamp base is screwed into the base 13, its threads, following the threads of the sleeve, ride up upon the arms 17 and force the latter outward, so that, when the lamp is in position in the socket, the arms 17 have been sprung outward so as to substantially follow the surface of the thread of the sleeve 13. The arms 17, by reason of their resiliency tend to return to their straight condition, and consequently exercise a powerful clamping effect upon the lamp base. This clamping effect is sufficient to retain the lamp in the socket in spite of any vibrations to which the latter may be subjected. At the same time, such clamping effect is not sufficient to prevent the insertion or withdrawal of a lamp when desired.

In Figs. 5-9 of the drawings, I have shown a modified form of my invention.

In these figures 20 represents an insulating base having a circular chamber 21 therein for receiving the threaded lamp contact 22. The chamber 21 is formed with two oppositely disposed pairs of vertical angular recesses 23. In each pair of recesses 23, is mounted a clamping member consisting of an upwardly extending arm 24, a downwardly extending arm 25 and a transverse member 26, such clamping members being formed by bending, from a single piece of wire. The arm 24 does not lie in the plane through 25 and 26, but extends off slightly to the side thereof as shown in Figs. 5, 8 and 9. The upwardly extending arm 24 and the downwardly extending arm 25 of each clamping member is disposed in one or the other of the recesses 23 of each pair of recesses, the extreme ends of these arms bearing against the walls of the recesses. The transverse portions 26 extend through slots 27 formed in the threaded sleeve 22 so as to follow the thread of such sleeve. When a lamp is inserted in the socket, the transverse members 26 are caused to spring outward, and, at the same time, the arms 24 and 25 are sprung toward a position in which they would occupy the same plane, Fig. 8. A clamping action is thus obtained similar to that described above with respect to the construction shown in Figs. 1-4.

It will be noted that, by means of my invention, I provide a lamp-gripping socket which is of an extremely simple construction, while being at the same time highly efficient. The lamp-clamping member is supported against the lateral pressure of the lamp base by the insulating body of the socket, whereby a construction which is reliable and not easily deranged is obtained. The gripping members being supported laterally merely by means of shoulders on the insulating body and vertically merely by means of the slots in the threaded sleeve, the assembling of the socket is a very simple matter, it being merely necessary to place the clamping members in position before assembling the portions of the socket. By means of the construction disclosed in Figs. 5-10, in which the required resiliency of the clamping members is obtained by the bending of the arms 24 and 25 as well as by the bending of the transverse member 26, I am enabled to apply the clamping members to sockets the castings of which are of comparatively small dimensions.

Having thus fully described my invention, what I claim as new and desire to obtain by Letters Patent is:

1. The combination with an electric lamp socket including an insulating body, of a resilient lamp-clamping member carried by said socket and adapted to be distorted by the lamp base when a lamp is inserted in the socket, said insulating body comprising

means for laterally supporting said clamping member.

2. The combination with an electric lamp socket including an insulating body having a shoulder thereon, of a lamp-clamping member with its side engaging said shoulder so as to be laterally supported thereby. 70

3. The combination with an electric lamp socket including an insulating body formed with a pair of shoulders and a depression 75 between said shoulders, of a lamp-clamping member with its side engaging said shoulders so as to be laterally supported at its ends thereby.

4. The combination with an electric lamp 80 socket including lamp contacts and means inclosing said contacts, of a resilient lamp-clamping member carried by said socket and adapted to be distorted by the lamp base when a lamp is inserted in the socket. 85 said inclosing means comprising means for laterally supporting said clamping member.

5. The combination with an electric lamp socket including lamp contacts and means 90 inclosing said contacts, said inclosing means being formed with a pair of shoulders and a depression between said shoulders, of a lamp-clamping member with its side engaging said shoulders so as to be laterally supported at its ends thereby. 95

6. The combination with an electric lamp socket including a threaded lamp contact having a slot therein and means inclosing said threaded contact, of a lamp-clamping member extending through said threaded 100 contact, said inclosing means comprising means for laterally supporting said clamping member.

7. The combination with an electric lamp socket including a threaded lamp contact 105 having a slot therein following the thread thereof and means inclosing said threaded contact, of a lamp clamping member extending through said threaded contact, said inclosing means comprising means for laterally supporting said clamping member. 110

8. The combination with an electric lamp socket including an insulating body, of a pair of oppositely disposed spring lamp-clamping members carried by said socket 115 and bearing against the said body and positioned in the path of the lamp base and adapted to be distorted by the lamp base when a lamp is inserted in the socket, said lamp-clamping members being laterally 120 supported by said insulating body.

9. The combination with an electric lamp socket including lamp contacts and means inclosing said contacts, said inclosing means being formed with two pairs of shoulders 125 having depressions between each pair, of a pair of cylindrically disposed lamp-clamping members with their ends engaging said shoulders so as to be laterally supported at their ends thereby. 130

10. In combination, a lamp socket, a resilient member having an intermediate part positioned in the path of the lamp base so as to engage, intermediate its ends, the 5 lamp base when a lamp is inserted into said socket, and means fixed with respect to said socket for supporting the ends of said member laterally.
11. In combination, a threaded lamp contact having a slot therein, a resilient member extending, at its center part, through said slot, and means fixed with respect to said threaded contact for supporting the ends of said member laterally.
15. 12. In combination, a threaded lamp contact having a slot therein following the thread thereof, a resilient member extending, at its center part, through said slot, and means fixed with respect to said 20 threaded contact for supporting the ends of said member laterally.
13. In combination, a threaded lamp contact having a plurality of slots therein following the thread thereof, a plurality of 25 symmetrically disposed resilient members each extending, at its center part, through one of said slots, and means fixed with re-
- spect to said threaded contact for supporting the ends of said members laterally.
14. The combination with an electric lamp 30 socket including an insulating body having a shoulder, of a spring bar in said socket having an end engaging said shoulder and having an intermediate part spaced from said socket member and positioned in the 35 path of the lamp base, whereby the spring bar will be distorted by the lamp base when the lamp is inserted in the socket.
15. The combination with an electric lamp 40 socket including an insulating body, of resilient lamp clamping means carried by said body and positioned to be laterally distorted when the lamp is inserted in the socket, said insulating body being provided with means for supporting said resilient 45 means to resist said lateral distortion.

In witness whereof, I have hereunto subscribed my name in the presence of two witnesses.

REUBEN B. BENJAMIN.

CHARLES G. COPE,
ANNE SOLOMON.

It is hereby certified that in Letters Patent No. 1,167,473, granted January 11, 1916, upon the application of Reuben B. Benjamin, of Chicago, Illinois, for an improvement in "Lamp-Clamping Sockets," an error appears in the printed specification requiring correction as follows: Page 2, line 127, claim 9, for the word "cylindrically" read *symmetrically*; and that the said Letters Patent should be read with this correction therein that the same may conform to the record of the case in the Patent Office.

Signed and sealed this 9th day of May, A. D., 1916.
